UNITED STATES PATENT OFFICE.

ISAIAH HALL, OF ASTON, BIRMINGHAM, ENGLAND.

DESIGN FOR A FURNACE FOR MELTING TYPE-METAL.

47,592.

Specification for Design.

Patented July 20, 1915.

Application filed July 1, 1914. Serial No. 848,485. Term of patent 14 years.

To all whom it may concern:

Be it known that I, ISAIAH HALL, subject of the King of Great Britain, residing at Aston, Birmingham, in the county of Warwick, England, have invented a new, original, and ornamental Design for Furnaces for Melting Type-Metal, of which the following is a specification, reference being had to the accompanying drawing, forming part thereof.

The figure presents a perspective view of a furnace for melting type metal showing my new design.

I claim:—

The ornamental design for a furnace for melting type metal, substantially as shown.

ISAIAH HALL.
